UNITED STATES PATENT OFFICE.

THOMAS A. LEWIS, OF NEW YORK, N. Y.

METHOD OF AND APPARATUS FOR LAYING SUBMARINE PIPE.

1,152,326.

Specification of Letters Patent. Patented Aug. 31, 1915.

Application filed May 27, 1915. Serial No. 30,638.

To all whom it may concern:

Be it known that I, THOMAS A. LEWIS, a citizen of the United States of America, residing at New York, in the county and State of New York, have invented certain new and useful Improvements in Methods of and Apparatus for Laying Submarine Pipe, of which the following is a specification.

10 This invention relates to an improved method of and apparatus for laying a submarine pipe.

More particularly, the invention is directed to laying a line of connected pipe sections from a floating vessel into a dredged trench under relatively deep water, and to improved apparatus for carrying on the work efficiently and expeditiously.

One of the objects of the invention is to 20 provide pipe laying apparatus which minimizes strain on the pipe joints when the work vessel is subjected to minor fluctuations by the water.

A further object is to provide an improved pipe launchway having means to scrape the trench bottom in advance of the pipe and having buoyancy devices to lighten the launchway and vessel and to control the action of the scraping means.

30 Another object is to provide a strong and substantially rigid launchway with means for connecting the same to the floating support, either resiliently or rigidly as desired, and also for enabling ready detachment of the launchway.

Other objects and advantages will be in part noted hereinafter in connection with the description of the accompanying drawings which illustrate a typical embodiment 40 of the invention.

The invention accordingly consists in the features of construction, combinations of elements and arrangement of parts which will be exemplified in the construction hereinafter set forth, and the scope of the application of which will be indicated in the following claims.

In the drawings, Figure 1 is a side elevational view of a vessel and apparatus for 50 conveying a pipe from above water to the water bed; Fig. 2 is a top plan view of the apparatus; Fig. 3 is a perspective view on an increased scale of a section of the pipe launchway; Fig. 4 is a similar sectional view on the line 4—4 of Fig. 1; Fig. 5 is a longitudinal sectional view of the submerged

end of the launchway; Fig. 6 is a sectional view on the line 6—6 of Fig. 5; Fig. 7 is a sectional view on the line 7—7 of Fig. 5; and Figs. 8 and 9 are respectively top and side views of a connection between the launchway and vessel.

The apparatus illustrated is particularly designed for laying a submarine line of water pipe at a depth below the range of 65 convenient diving operations and in a manner to insure permanently water-tight pipe joints and thorough reliability of the line. In general, it may be stated that the pipe sections are successively coupled together 70 above water and conveyed on a curvilinear launchway to the bottom of a previously dredged receiving trench in the water bed. This operation is expeditiously effected by advancing the launchway in predetermined 75 steps so that the pipe, held at one end by its already laid length, slides down the launchway and straightens on the trench bottom. An additional section is then coupled above 80 water and the operation successively repeated.

Referring more particularly to the drawings, there is shown a barge or other suitable floating support 10 provided with requisite accessories such as derricks, etc., and 85 preferably having a central longitudinal end opening or well 11 for receiving the upper end of a reinforced launchway or cradle 12. The deck space on opposite sides of the well 11 may be conveniently utilized for storing 90 pipe sections to be coupled together on the launchway, adjacent the upper end of which is located a melting pot 13 for material to pack the joints. The pipe sections are coupled together by bell joints which permit 95 limited swiveled movement and the launchway is curved gradually so that the pipe will assume a straightened condition when laid without undergoing excessive angular displacement during the lowering thereof. In 100 practice, the pipe supported by the launchway may be of great weight and the launchways are accordingly of reinforced metal structure. As illustrated, the launchway comprises upper and lower pairs of spaced 105 longitudinally extending body beams 14 and 15 trussed together by vertical brace beams 16 and diagonal brace beams 17. A transversely curved or concave guideway 18, preferably of boiler metal, is provided for slidably supporting the pipe and is disposed between the upper longitudinal angle beams 14

110

and the diagonal struts 17. This guideway, when continuous, is also preferably foraminous, having numerous water passages 19 to facilitate raising and lowering.

5 At the lower or submerged extremity of the launchway, a scraper or smoothing device 24 is provided to clear the trench bottom of silt or other deposit in advance of the pipe, and thereby insure an even and permanent bed for the line. To this end, 10 the scraper is rigidly-attached to the launchway for dragging by the latter and is preferably provided with a longitudinally straight and transversely convex under surface 25. Also when the scraper is a separate device rigidly attached to the launchway as shown, it is provided with a concave upper surface 26 forming a continuation of the guideway 18. The forward end 15 of the scraper may also be sharpened as at 27 and dished thereabove at 28 and 28^a to receive one or more jet nozzles 29, 29^a from which air or water may be discharged under pressure to assist the clearing action of the 20 scraper. A compressor or pump 30 is provided on the vessel for this purpose to supply fluid to the jet nozzles through conduits 31.

As above mentioned, the weight of the 30 connected pipe sections carried on the launchway may be very great. For example, with a 36 inch pipe line, the weight of such sections approximates seventy-five tons. It will thus be seen that the load on 35 the vessel, even after allowing for the partial buoyancy of the line, is frequently extreme. Accordingly there is provided additional buoyant means to relieve the medial strain on the launchway and to substantially decrease the load on the vessel. As 40 illustrated, one or more buoyancy tanks 33, 34 and 35 are secured to the launchway at a submerged point intermediate its ends. The buoyancy of tanks 33 to 35 is designed 45 to be such that the pressure of the lower or scraper end of the launchway on the trench bottom is sufficient to properly clear away silt without acting as a plow, and without imposing a severe drag on the vessel when the latter is snubbed ahead to lower 50 the pipe. If desired, the buoyancy of the tanks may be varied at will by supplying thereto or expelling therefrom water ballast. A convenient manner of effecting such buoyancy control is by the compressor on the vessel and valved connections with the tanks. It will be understood, however, that other means may be employed.

The connection between the cradle launchway and vessel is such that fluctuations of the former due to surface water variations are transmitted in a reduced degree to the latter. Both longitudinal and transverse strain on the pipe couplings is thus minimized. As illustrated, the launchway is at-

tached above water to the vessel by a pivotal, resilient connection including bearing frames or brackets 36 fixed to the vessel on opposite sides of well 11 for supporting a pivoted bolt 37 which passes through registering slots 39 in extension plates 38 rigidly fixed to the upper end of the launchway. Cushioning means in the form of strong springs 40, 41, arranged in pairs, are provided to resiliently hold the launchway plates 38 so that the bolt 37 is disposed medially in the slots 39. Said springs are hooked or otherwise secured to the plates 38 and are secured at their opposite ends to fixed brackets 44 by nuts 43 on the threaded bolt ends 42. The normal tension of the spring is thus capable of adjustment and the vessel and launchway are permitted limited relative movements. There are further provided threaded set bolts 45 on the plate 38 and adjustable to abut shoulders 46 on pivot shaft 37 or its supporting frame for thereby positively holding the launchway against relative downward movement. Similarly, wedges or chock blocks 47 are provided for insertion in the slots 39 below the shaft 37 for completing a rigid connection of the launchway with the vessel. At the same time the launchway may be quickly detached from the vessel by withdrawing the shaft 37. In stress of weather, or in case of temporary abandonment of the work, the pipe may be sealed by a bulkhead and the launchway further buoyed and anchored, whereupon the vessel may be removed to be returned when desired for resuming the work. A second connection is also preferably provided between the vessel and the submerged part of the launchway. As illustrated, this connection comprises a chain 21 and a heavy spring 21' connected by a sling 22 with a medial portion of the launchway and having its upper end received on a windlass 23 or otherwise attached to the vessel. The angle of the launchway may thus be positively controlled to compensate for different water depths and the strain on the launchway further reduced. It is to be noted, also, that the interposition of spring 21' renders this reinforcing connection resilient and thus tends to further minimize relative movement of the launchway above described.

Assuming the pipe line to be partially laid as illustrated, the continuing operation with the apparatus is substantially as follows: The vessel is firmly anchored against lateral drifting in any direction and the connection between the upper end of the launchway and the vessel is rendered resilient or yieldable in the manner described. A pipe section is then suitably coupled to the connected line. By set bolts 45 and blocks 47 the launchway is then rigidly secured to the vessel, though pivotal move-

ment is permitted, and the vessel is snubbed ahead or otherwise advanced sufficiently so that the pipe line will slide in the guide 18 and deposit a section on the trench bottom, the latter being immediately prepared therefor by the scraper 24 which is dragged with the launchway. Since the load of the launchway is particularly heavy during such advancement of the vessel, it will be seen that the provision of the rigid connection described is very desirable to temporarily relieve the cushioning springs 40, 41. The steps of the operation described are then progressively repeated.

Having thus described my invention, what I claim as new and desire to secure by Letters Patent is:

1. In apparatus for the purpose set forth, in combination, a floating support, a launchway and spring means between said support and said launchway for permitting the former to rise and fall to a greater degree than the latter.

2. In apparatus for the purpose set forth, in combination, a floating support, a launchway, a yieldable connection between said support and launchway for permitting the former to rise and fall to a greater degree than the latter, and means for rendering said connection substantially unyielding to insure equal advancement of said support and launchway.

3. In apparatus for the purpose set forth, in combination, a floating vessel, a trussed metal launchway, a resilient pivotal connection between said elements including a plurality of cushioning springs interposed therebetween, and means to render said connection unyielding while permitting relative pivotal movement.

4. In apparatus for the purpose set forth, in combination, a floating vessel, a trussed metal launchway, spring means connecting said support and said launchway for per-

mitting the former to rise and fall to a degree greater than the latter and a buoyancy tank secured to said launchway.

5. In apparatus for the purpose set forth, in combination, a floating vessel, a launchway, spring means for attaching said launchway to said vessel, a submerged buoyancy tank secured to said launchway and means to control the buoyancy of said tank.

6. In apparatus for the purpose set forth, in combination, a floating vessel, a launchway pivotally connected at one end to said vessel, and a supporting connection including resilient means between said vessel and a medial submerged portion of said launchway.

7. In apparatus for the purpose set forth, in combination, a floating vessel, a trussed metal launchway pivotally attached thereto, a sling for supporting said launchway remote from the attachment of the latter to said vessel, said sling including spring means and a buoyancy tank carried by said launchway to relieve said sling.

8. In apparatus for the purpose set forth, in combination, a floating vessel, a curvilinear launchway suspended therefrom and provided adjacent its submerged end with a scraper, and a buoyancy tank secured to said launchway and tending to regulate the action of said scraper.

9. In apparatus for the purpose set forth, in combination, a floating support, a reinforced launchway having its major length submerged to guide a pipe line from said support, and a plurality of spaced cushioning connections between said support and said launchway to substantially free the latter from vibrations of the former caused by water fluctuations.
